Attn:

UNITED STATES PATENT OFFICE.

JOHN H. CHRISTIE, OF EAST PROVIDENCE, RHODE ISLAND, ASSIGNOR OF
ONE-HALF TO JOHN H. CHURCH, OF SAME PLACE.

PERMUTATION-LOCK.

SPECIFICATION forming part of Letters Patent No. 621,992, dated March 28, 1899.

Application filed April 13, 1898. Serial No. 677,438. (No model.)

To all whom it may concern:

Be it known that I, JOHN H. CHRISTIE, of East Providence, in the county of Providence and State of Rhode Island, have invented a new and useful Improvement in Permutation-Locks; and I hereby declare that the following is a full, clear, and exact description of the same, reference being had to the accompanying drawings, forming part of this specification.

This invention has reference to an improvement in padlocks in which the hasp is locked and unlocked by the partial rotation of one or more locking-disks.

The object of the invention is to facilitate the adjustment of the combinations controlling the opening of the lock and simplify its construction.

Figure 1 is a side view of the padlock. Fig. 2 is an edge view of the same. Fig. 3 is a side view of the open lock. Fig. 4 is a side view of the detachable side of the lock. Fig. 5 is a transverse sectional view of the lock. Fig. 6 is an end view of part of the detachable cover, showing one of the locking-flanges. Fig. 7 is a top view, partly in section, of the locking-bolt connected with the locking-arm of the hasp.

Similar numerals of reference indicate corresponding parts in all the figures.

In the drawings, 8 indicates the circular disk forming one side of the lock, 9 the circular rim forming the edge of the lock, and 10 a thumb-post extending through the side 8. The disk 11, provided with the unlocking-recess 12, is secured to and turns with the thumb-post 10. The serrated disk 13 is centrally secured to the thumb-post 10 by the screw 14. It is provided with the segmental slots 15 15 and is secured to the disk 11 by two screws extending through the segmental slots. The serrated disk can be turned on the screw 14 and adjusted to the desired position when it is secured to the disk 11 by the screws extending through the segmental slots 15; 16, the unserrated portion of the periphery of the disk 13. The rim 9 is perforated to receive the stem 17 of the hasp 18 and also perforated to receive the dowel end 19 on the opposite side of the hasp 18. The spring 20, secured to the inside of the rim 9, is bent sharply at a right angle at its upper

end. It bears on the unserrated portion 16 of the periphery of the disk 13, and when the disk 13 is turned the spring enters the serrations with a click that can be readily heard.

The lower end of the stem 17 of the hasp 18 is provided with the hook 21, which engages with the hooked post 22, secured to the inside of the rim 9. The T-shaped locking-bolt 23 is connected with the stem 17 of the hasp by the link 23'. The T-shaped end of the locking-bolt 23 is supported by the pins 24 24, projecting inward from the rim 9. The pins 25 25, projecting inward from the rim 9, serve to secure the cover 26 to the rim 9.

The parts connected with the cover 26 are duplicates of the parts connected with the side 8 and consist of the thumb-post 10', the locking-disk 11', secured to the thumb-post 10' and provided with the unlocking-recess 12', the serrated disk 13', with the segmental slots 15', and the unserrated portion 16' of the periphery of the disk 13'. The spring 20' cooperates with the serrated disk 13'.

From the inside of the cover 26 project the flanges 27, having on one end the hook 27', each one of which may by the partial turning of the cover engage with one of the pins 25. One of these flanges 27 is provided with a locking-recess into which the projecting end 19 of the hasp 18 enters, and as long as the hasp is locked the cover cannot be removed.

The operation of the lock is as follows: As long as the T-shaped end of the locking-bolt 23 rides on the periphery of one of the two disks 11 and 11' the bolt holds the stem 17 of the hasp 18 in the hooked and locked position, (shown in Fig. 3,) and only when both of these disks are turned so that the T-shaped end of the locking-bolt 23 can enter the unlocking-recesses 12 and 12' simultaneously can the stem 17 be moved so as to disengage the hook 21 from the hook 22. When this is done, the hasp can be raised to remove the lock from the object to which it is secured, and, if desired, the cover 26 may be removed by partially turning the same. By adjusting the serrated disks 13 and 13' any desired combination may be arranged which will have to be known to open the lock. As shown in the drawings, the serrated disk 13 is adjusted so that the serration 8 is opposite the index-mark on the disk 11, while the serration 5 of

the serrated disk 13' is opposite the index-mark on the disk 11'. To open the lock so adjusted, the thumb-post 10 has to be turned in the direction indicated by arrows in Figs.

5. 3 and 4 until the spring 20 has clicked eight times and the thumb-post 10' until the spring 20' has clicked five times, when the unlock-ing-recesses 12 and 12' will be in position to allow the bolt 23 to enter the same simulta-neously and permit the unhooking and par-tial raising of the hasp.

Having thus described my invention, I claim as new and desire to secure by Letters Patent—

15. In a lock of the nature herein described, the combination with the two sides and the rim of the casing, a hasp having a long stem provided with a hook at one end and a short

stem on the other end, a hook within the cas-ing, and openings in the rim for the insertion 20 of the projecting ends of the hasp, of thumb-posts on each side of the casing, two locking-disks one of which is secured to each post, two partially-serrated, adjustable index-plates, and a bolt flexibly connected with the long 25 stem of the hasp; whereby when the recesses of the two locking-plates register with the locking-bolt, the long stem of the hasp may be unhooked and the hasp opened, as described.

In witness whereof I have hereunto set my 30 hand.

JOHN H. CHRISTIE.
